Albert D. Grover,

by *John W. Grover*
his Atty.

UNITED STATES PATENT OFFICE.

ALBERT D. GROVER, OF LONG ISLAND CITY, NEW YORK.

TAILPIECE FOR STRINGED MUSICAL INSTRUMENTS.

Application filed October 25, 1924. Serial No. 745,856.

My invention relates to new and useful improvements in tail pieces for stringed musical instruments.

The principal object of my invention is 5 to provide a one piece tail piece which may be used with equal facility on substantially any banjo instrument, i. e. for string tenor-banjo, ukelele banjo, five string standard banjo, six string guitar banjo and the eight 10 string mandolin banjo.

Strings for the above instruments are usually provided at their attaching ends with either loops or balls, and it is a further object of the present invention to provide 15 the tail piece with a plurality of prongs so spaced from each other as to enable either type of string end to be attached thereto.

A further object of my invention is to provide a covering for the rough ends of the 20 strings so as to prevent the latter from catching and tearing the clothing of a player.

The design of the present tail piece is such that the device may be manufactured very cheaply and at the same time is capable 25 of performing substantially all of the functions of the more costly tailpieces now on the market.

The invention is illustratively exemplified in the accompanying drawings, in which, 30 Figure 1 is a perspective view of my improved tail piece and the associated parts of a top hoop of an instrument; Figure 2 is an elevational view of the tail piece looking towards the end of the instrument; Figure 3 is a transverse sectional view taken on the lines 3—3 of Figure 2; Figure 4 is a plan view of the tail piece; Figure 5 is a 35 sectional view taken on the lines 5—5 of Figure 4; and Figure 6 is a sectional view 40 similar to Figure 5 showing a slightly modified construction for attaching the tail piece to the top hoop.

Referring to the drawings, 10 denotes the top hoop of a banjo instrument, 11 the rim 45 and 12 the head which is stretched over the usual rings 13 and 14 and held under tension by adjustment of the top hoop 10.

My improved tail piece 15 consists of one piece of material which is bent at right 50 angles to form a string cover 16 and upright portion 17. The sides of the portion 17 are cut to form inverted L-shaped vertical bracket flanges 18 which are bent at right angles to the plane of the upright portion 55 so as to bring the base arms of the L beneath the cover portion 16, as clearly illustrated

in Figure 1. The free ends of the base arms of the L are provided with depending projections or teeth 17' which are adapted to hook over the upper end of the top hoop 60 10. The upright portion 17 adjacent its upper end is provided with a string slot or opening 19, which is formed by cutting an inverted U-shaped slit in the metal and then bending the material inwardly to provide 65 a lip 20 over which the strings pass from under the cover piece 16. The slot 19 is disposed so that the surface of the turned in portion of material forming the lip 20 is 70 level with the surface of the head 12 and top hoop 10, as clearly illustrated in Figure 3. It will be clear that the bend in the lip 20 forms a rounded edge upon which the strings 75 may rest without fear of any injury being done to them.

Spaced below the slot 19, in the upright portion 17, is a second aperture 21, the upper side of which is provided with a plurality of string receiving members, preferably in the form of depending prongs 22, which 80 are curved outwardly and downwardly and which are preferably tapered to a point at their free ends in order to aid in the operation of inserting the strings. Since the portion 17 of the tail piece is spaced slightly 85 from the top hoop 10 by the position of the L-flanges, it will be clear that the ends of the strings will have ample space in which to be concealed between the prongs 22 and adjacent portion of the top hoop 10. The 90 ordinary exposed rough loose ends of strings in this type of musical instrument have always been a source of trouble in the way of causing injury to such parts of the garments 95 with which they are brought into contact. The generous curved portion of the prongs 22 almost entirely covers the opening 21 so that once the ends of the strings are attached over the prongs there is small chance 100 of having any stray parts which will not remain in the pocket beneath the portion 17.

The position of the tail piece with respect to the banjo is further determined by means 105 of the usual bracket 23 comprising a member projecting from the periphery of the rim 11 and having a transverse bore, arranged parallel to the axis of the head and rim, and adapted to receive a screw 24 the head of which bears against a lateral integral projection 25 bent outwardly from 110 the lower end of the portion 17, the stem of

the screw being projected through an elongated slot 26 in the projection 25. The lower free end of the screw 24 is threaded to receive a nut 27 adjustable against the bracket 23 to tighten the position of the tail piece.

According to the modified construction shown in Figure 6, the lip 20' is a trifle longer than the lip 20 of the other design, and the end thereof is bent downwardly at right angles so as to be capable of engaging the groove 10' in upper side of the top hoop 10. This design does not require the flanges 18 to be provided with the teeth 17' since the turned end of the lip 20' engaged in the groove 10' insures the tail piece against any twisting action. The turned down end of the lip 20' is of necessity slightly curved to conform to the curve of the groove in the top hoop 10.

The essential features of my invention are, first, the one piece construction of a tail piece having integral string cover and receiving members; second, the spaced relation of the prongs to receive substantially any string combination used in connection with banjo constructions; third, the protection afforded the garments of the player by the design of the prongs and their position relative to the adjacent opening in the tail piece; and fourth, the upper slot through which the strings pass to the head of the instrument and the provision of the lip 20 to support the strings in any combination without injury to the same from sharp edges, etc.

What I claim is:

1. A tail piece for stringed musical instruments, comprising an integral cover plate and rim plate, the latter being provided with spaced prongs integral therewith and overlying an opening in the rim plate,

said rim plate being further provided with a string slot having one edge turned inwardly to form a lip over which the strings are disposed in their passage from the prongs to the head of the instrument.

2. A tail piece for stringed musical instruments, comprising an integral angular member forming the cover plate and rim plate, the rim plate being provided with integral wing bracket portions comprising substantially inverted L-shaped members disposed at an angle to the rim plate, one arm of each L-shaped member being provided with a projection to engage over the rim of the instrument.

3. A tail piece for stringed musical instruments, comprising an integral angular member, one portion thereof being provided with bracket flanges to engage a portion of the instrument and to support the other portion of the member, the portion having the brackets being further provided with an outwardly projecting slotted flange bent from a portion of the lower end of the member, the material of the first named portion being slotted to form separate openings, the lower edge of one opening being bent inwardly to form a lip, and the other opening having its upper edge bent to form spaced, inwardly curved tapered prongs disposed outwardly in a curve to receive the string ends of the instrument.

4. A tail piece for stringed musical instruments comprising an integral cover plate and rim plate, the latter being provided with a string slot having an edge bent inwardly to engage over a portion of the instrument and then at an angle to seat into the said portion.

In testimony whereof I affix my signature.

ALBERT D. GROVER.
